Stockholm, Sweden, a corporation of Sweden

Application April 10, 1947, Serial No. 740,585

15 Claims. (Cl. 299—69)

1

This invention relates to dish washing apparatus wherein dishes or the like are cleansed by means of one or more jets of liquid, the jets being directed towards movable jet direction-changing means, hereinafter termed "diverting means."

According to the present invention, in dish washing apparatus of the character described, jet producing means is provided comprising a nozzle adapted to discharge a jet of liquid and jet-diverting devices arranged so as to be impinged by the liquid jet discharged from said nozzle and movable transversely of the direction of the nozzle discharge.

Preferably the apparatus, according to the invention, includes a plurality of jet-diverting devices having different deflecting characteristics which move in succession transversely of the direction of the nozzle discharge.

The constructions above-mentioned provide the spraying with liquid of the articles being treated from a large number of points in the washing receptacle and further by differently directed jets from such points.

The spraying action is increased by making the nozzle opening or openings and the jet-diverting means movable and preferably rotatable, the relative movements being preferably obtained by different directions of movement and/or by different angular velocities being imparted to the two members. Such relative movement may be simply produced by constructing and arranging the nozzle openings and the diverting members as to cause the member containing the openings and said diverting means to rotate in opposite directions due to the reactive and applied forces respectively of the jets.

The invention will be hereinafter more fully described with reference to the embodiments illustrated in the accompanying drawings, in which:

Fig. 1 shows a dish washing machine in transverse section fitted with spraying devices according to the invention at its base and on the cover;

Fig. 2 shows the same machine in horizontal section taken along the line II—II of Fig. 1;

Fig. 3 shows a spraying device according to the invention partly in section along the line III—III of Fig. 4;

Fig. 4 shows the spraying device in plan;

Fig. 5 is a section along the line V—V of Fig. 4;

Fig. 6 is a section on an enlarged scale along the line VI—VI of Fig. 4;

Fig. 7 shows a modification of the detail shown in Fig. 6;

2

Fig. 8 shows diagrammatically the cooperation of a jet opening with the diverting means;

Fig. 9 shows a modified embodiment of the central member of the spraying device having a speed regulating device built into said member, this figure being a section along the line IX—IX of Fig. 10;

Fig. 10 shows the same device in section along the line X—X of Fig. 9;

10 Fig. 11 is a section along the line XI—XI of Fig. 12;

Fig. 12 shows the spraying device from above with a modified speed regulating device, one portion of the former device being removed to show 15 underlying parts;

Fig. 13 shows in plan view a further embodiment of the spraying device;

Fig. 14 shows the central member of the spraying device in a vertical section along the line 20 XIV—XIV of Fig. 16;

Fig. 15 is a section along the line XV—XV of Fig. 14;

Fig. 16 is a section along the line XVI—XVI of Fig. 14;

25 Fig. 17 shows a section through the jet head along the line XVII—XVII of Fig. 18; and

Fig. 18 shows the jet head from above, partly in section along the line XVIII—XVIII of Fig. 17.

Referring to Figs. 1 and 2, 10 designates the 30 casing of the dish washing receptacle having a base 11 and cover 12. In this embodiment a spraying device designated generally by 13 is located at the base of the receptacle and another on the cover 12. The spraying device is rotatably mounted on the base and cover respectively

35 of the apparatus. Member 14 contains an inlet channel 15 for the washing water supplied through the conduits 16, 17 and 18, which in known manner communicate with a main supply conduit or with a pump (not shown) for the machine. The conduit 16 which supplies water to the cover spraying device, is in known manner formed with a hinge 19, so that the cover of the apparatus may be opened and closed in

40 spite of the rigid conduit connected thereto. The receptacle contains, between the two spraying devices, a wire base 20 and a frame 21 for the dishes or the like. An outlet conduit for the used washing liquid is shown at 22.

45 In the embodiments of the spraying device shown more in detail in Figs. 3—12, an S-shaped support 23 is mounted on the member 14 which is formed with a journal 24 (Fig. 3) at its face directed inwardly of the receptacle. The device

50 for changing the direction of the jet, hereinafter 55

termed "diverting means" is formed on the support 23. In the embodiments illustrated, such means consist of two series of grooves 25 disposed on the two limbs of the support. In the center of and above the support is arranged a jet head 26, in which nozzles 27 cooperating with the diverting means 25 are provided. This jet head 26, which is of cylindrical shape, is rotatably mounted between a guide washer 28 and a guide screw 29, the latter itself being also shaped as a guide washer.

In the embodiment shown in Figs. 3 and 4 the two nozzles 27 open tangentially from a circular bore 30 formed in the jet head, said bore communicating with the inlet channel 15 through a T-shaped channel 31 formed in the screw 29. The grooves 25 provided on the S-shaped support 23 are directed so that the longitudinal axis of each groove, as seen in plan in Fig. 4, points towards the inner end of the axis of the nozzle. As the axis of each nozzle is tangential relatively to the bore 30 of the jet head 26, the axis of each groove will also be tangential relatively to said bore, as illustrated by the dotted line 32 in Fig. 4.

In the arrangement of the grooves 25 illustrated in Fig. 6, the longitudinal axis of each groove lies in a vertical plane, while in the arrangement shown in Fig. 7, the grooves 25' are inclined to the vertical. The grooves arranged on one half of the support 23' are inclined so as to direct the jets issuing from said grooves inwardly towards a plane passing through the axis of rotation parallel to the direction of the jet entering said grooves, while the grooves arranged on the other half of the support are inclined so as to direct the jet issuing therefrom outwardly from said plane. Such a plane P, which passes through the axis of rotation and is parallel to the direction of the jet 32 issuing from one of the nozzles 27 at a particular instant, is indicated by a dotted line in Fig. 4. The grooves on one-half of the support 23' are inclined so that the jets emerging from the grooves, at a particular instant like that indicated in Fig. 4, are inclined in a direction toward the plane P; and the grooves on the other half of the support are inclined so that the jets emerging from the grooves, at a particular instant like that indicated in Fig. 4, are inclined in a direction from the plane P.

The result is that also in those positions of the jet head 26 wherein the jet issuing from the nozzles 27 is directed parallel to those surfaces of the dishes which are to be treated, for example, the two faces of a number of plates stacked behind one another, these surfaces will be impacted by the jets deflected by the diverting means at an angle such that the cleansing effect of the jets is efficiently utilized.

As shown in Figs. 6 and 7, the cross section of the grooves at their base is semi-circular and their walls extend parallel to one another, the wall spacing being accommodated to the dimensions of the nozzles 27 and the grooves also being shaped so that the liquid will leave the groove in the form of a non-spreading jet, that is distinct from a spray. They are made so as to have the same radius of curvature in radial cross section, as seen in Fig. 5, but comprise arcs of different length, as indicated in Fig. 8. This is effected by forming the outlet edge, at the regions the jets emerge from the groove as an undulating line (Figs. 3, 6 and 7). To obtain further variations of the angle of the issuing jets the undulating lines of the two series of grooves arranged on

the support are formed so as to be relatively displaced, so that any two grooves, symmetrically located relatively to the center of rotation, are of different heights.

In the diagram of Fig. 8, the nozzle corresponds to the jet head with its jet openings 27 and the guiding means 25 shown correspond to imaginary sections through different grooves, one being located at the lowest point of the undulating line, another between the lowest and the highest point of the said line and the third at its highest point. As will be seen, the lower portion of each groove is directed towards the incoming jets. The directions of the issuing jets, produced in the different cases of the selected example are also indicated, from which will be seen that due to the differing lengths of the arcs, the jets issue at different angles, some being diverted through more than 90°.

The device operates in the following manner. If washing water is supplied to the channel 15, either from a water conduit or from a pump forming part of the dish washing apparatus, it flows through the channel 31 to the bore 30 and the nozzles 27. The jets issuing therefrom will impact the grooves on the support, so that the latter, due to the applied pressure, is caused to rotate. Simultaneously, the jet head 26 will rotate in the opposite direction due to the reactive pressure. During rotation the jets issuing from the nozzles will successively hit the different grooves and will there be deflected towards the dishes in different directions. Since the support with the grooves extending along the same, as shown in Fig. 2, stretches to the vicinity of the walls of the receptacle, the jets thus deflected will also be directed towards the dishes from a large number of different points in the receptacle. It is clear that by providing a spraying device which is arranged centrally of the apparatus, the dishes will be sprayed not only with jets directed obliquely outwardly from the center, but also with jets directed obliquely inwardly from the outside, as indicated by the deflected jets 32' in Fig. 8.

Figs. 9 and 10 show a further embodiment of jet head, modified for manufacturing production, which differs from the above described, mainly by being provided with a device for regulating the speed of rotation. In this case the rotating member generally designated by 26', and mounted between the guide washer 28 and the guide screw 29', comprises two halves 40 positioned relatively to each other by guide pins 41 and held together by screws 42. Between these two halves a centrifugal regulator, of known type, is arranged. It consists of two weights 43, mounted to pivot about the axes 44 and counterbalanced by springs 45. In this construction, the two weights 43 and the springs 45 are dimensioned so that, at the maximum allowed speed, the weights swing outwardly and abut against a stationary edge 46 of the guide screw 29' and thus act as brake blocks.

The nozzle openings 27 formed in the halves in this case comprise separate nozzles 47 screwed into the dividing plane of the halves, the said nozzles being in known manner formed so as to produce a non-spreading jet.

Figs. 11 and 12 show another modification of the spraying device which differs from those hereinbefore described by being provided with a hydraulic brake for regulating the speed of rotation. The brake consists of a gear wheel pump of known type, the outlet of which is throttled, as will be explained presently. The center member 14" is formed with a toothed rim 50, which co-

5

acts with two gear wheels 51, mounted in a chamber 52, in the support 23" where they are retained by a cover 53. The washing water is supplied to this "pump" from the washing receptacle through a channel 54 opening in the vicinity of the jet head and is discharged through leakages formed between the brake parts which inherently serves as a throttled outlet. Accordingly, by varying the extent and magnitude of such leakage which can take place, the braking action of the pump may be increased or decreased by variation of the resistance to flow of the water therethrough. In this device, the water itself serves as the braking medium.

In the embodiment shown in Figs. 13 to 18, the spraying device, as in the previous figures is designated generally by 13 and the support by 23", the latter being provided with three arms. The jet diverting grooves 25 of one of these arms extend vertically as shown in Fig. 6, the grooves 25" of another of the arms extend at an inclination as shown in Fig. 7 and the grooves 25' of the third arm are inclined in the opposite direction as above described in connection with Fig. 7. In the center of the support, the jet head 26"" is mounted in the inlet channel 15 of the center member 14"".

The jet head consists of two halves 60 and 61 which are held together by screws 62. In the dividing plane of the halves there are three channels 63 which communicate with the inlet channel 15. In the mouth of the channels 63 nozzles 41 are inserted, as in the embodiment shown in Figs. 9 and 10. A spindle 64 is fixed to the upper half 60 of the jet head and rigidly carries a ring 65 at its lower end. This ring 65 and a well formed in the lower jet head half 61 form together a bearing for the jet head in the inlet channel. This bearing is constructed so that the liquid pressure will not cause displacement of the jet head 26"" since the pressure acting on the ring 65 is equal to the pressure on the lower jet head half 61. The spindle 64 is provided with a bore 67 in order to drain any leakage water from the underside of the ring 65.

The lower half 61 of the jet head carries a gear wheel 68 cooperating with two gear wheels 69 mounted on a bracket 70 rigidly connected to the center member 14", to form a planetary gearing together with a ring gear 71 associated with an hydraulic brake housing 72. The brake housing 72 is connected to the support 23"" by means of screws 73 and takes part in the rotation of the support, so that the abovementioned gearing thus controls the relative movement of the support and the jet head. The main parts of the abovementioned brake comprise the brake housing 72, a blade holder 74, six blades 75 and a cover 76. The inlet of the brake consists of a narrow channel 77 drilled obliquely in the upper side of the housing and communicating with the washing receptacle in the vicinity of the jet head.

The blade holder 74 is rigidly connected to the center member 14"" by means of a projection 78 or the like. The blades which are guided radially by grooves 79 in the holder 74 are caused to abut permanently against the outer surface of the housing 72 by means of a cylindrical cam 80 formed on the cover 76 and concentric with the outer wall surface of the housing.

If washing liquid is supplied to the channel 15 it will flow to the nozzle openings 27. The support 23"" is thus caused to rotate in a clockwise direction and the jet head 26"" in counterclockwise direction. Due to the washing liquid flow-

6

ing from the receptacle into the brake through the channel 77 the brake will retard the rotation of the support and by means of the gearing also that of the jet head. As in the previously described embodiment of Figs. 11 and 12, leakage formed between the brake parts inherently function as a throttled outlet. Hence, the braking force is determined by the tightness of the hydraulic brake, so that the tighter the brake is, the slower is the rotation. A predetermined clearance is thus necessary between the blades 75 and the housing 72 of the brake according to the desired speed of rotation.

Although the invention has been fully described in connection with several illustrated embodiments, it is obvious that its application and its details may be varied. For example, the jet head and/or the jet diverting devices may be positively driven from a separate driving motor, or one of them may be driven by the washing water and the other by suitable gearing from the former, if desired, against the direction of the jet forces, so as to obtain an increased impinging force of the jet. If desired, the jet head and the spraying device may rotate in the same direction at different angular speeds. In the case of a positive drive the jet channels may be arranged radially in the jet head.

In view of the foregoing, it will now be understood that an improved dishwashing apparatus has been provided in which each rotatable jet head 26 in the embodiment of Figs. 1 to 6 constitutes a nozzle structure having an opening for discharging liquid therefrom in a horizontal plane. The S-shaped support 23 constitutes a liquid deflecting or diverting unit arranged to be acted upon by liquid issuing from the nozzle openings 27 for directing liquid toward different parts of a batch of dishes adapted to be washed in the receptacle 10.

In the preferred embodiments of the invention the nozzle structure 26 rotates in one direction by the reaction force developed by the discharged liquid and the liquid deflecting or diverting unit 23 rotates in the opposite direction by the impact force of the discharged liquid acting thereon. Accordingly, an arrangement has been provided in which the nozzle structure 26 moves with respect to the liquid deflecting unit 23 and the liquid deflecting unit moves with respect to the nozzle structure 26. Also, in the preferred embodiments the fixed or stationary axis about which the nozzle structure 26 rotates is parallel to and in the immediate vicinity of the fixed or stationary axis of rotation of the liquid deflecting unit 23; and each liquid deflecting unit rotates in a horizontal plane which is substantially parallel to and in the immediate vicinity of the horizontal plane in which liquid is discharged from the nozzle structure 26.

Essentially, the rotatable liquid deflecting unit 23 comprises the angularly movable arms which provide a surface that passes and moves through a given area during its rotation and different groove portions 25 of which are operable in succession at different distances from the nozzle openings 27 and at different regions in such area to change the direction of liquid discharged from the nozzle openings in a multiplicity of directions at different acute angles to the horizontal plane in which liquid is discharged from the nozzle structure 26, as diagrammatically seen in Fig. 8.

Hence, when the nozzle structure 26 moves in its path of movement from a starting point back

to such starting point during one revolution and the liquid deflecting unit likewise moves in its path of movement from a starting point back to such starting point, liquid is deflected in the general direction in which the axis of rotation of the nozzle structure 26 extends, the liquid being deflected from certain regions of the deflecting unit 23 in a radially inward direction and from other regions in a radially outward direction, as also diagrammatically seen in Fig. 8.

During rotation of each nozzle structure 26, the openings 27 therein are constantly discharging liquid in different radially extending directions. The liquid deflecting units are formed with grooves 25 to provide surface characteristics in which deflected liquid leaves the deflecting units in the form of a compact liquid jet. As best seen in Fig. 4, axes of the liquid inflow ends of the grooves or passages 25 and the axes of the nozzle openings 27 are substantially tangential to the same circle whose center is located at the axis of rotation of the nozzle structure 26.

It will now be understood that the liquid deflecting unit 23 constitutes a rotatable liquid diverter having a body including a central hub section and arms 23 extending radially outward therefrom. Each arm 23 of the liquid diverter body includes a first region 25a having portions, as indicated at 25b, 25c and 25d in Fig. 4, for example, at successively different radial distances from the axis of rotation of the diverter, which are initially impinged by liquid discharged from the openings 27 of the nozzle. Further, each arm 23 of the liquid diverter body includes a second region, indicated at 25e in Fig. 4, to which liquid passes from the first region 25a and from which second region diverted liquid emerges and is directed toward the dishes to be washed. The second region 25e of each arm 23 includes liquid emerging portions at successively different radial distances from the axis of rotation of the liquid diverter body which are respectively inclined radially outward from and radially inward toward the axis of rotation of the liquid diverter body.

While the grooves 25 essentially have the same radius of curvature, the lengths of different grooves vary, as best seen in Figs. 6 and 7, the lengths of the grooves extending through angles in a range which varies from a value below to a value above 90°. Further, the grooves 25 desirably are formed with semi-circular bottoms and substantially parallel walls. As described above in connection with the embodiments of Figs. 11 and 12 and also Figs. 13 to 18, it is desirable to embody provisions to govern the maximum speed of the liquid deflecting unit 23 so that the force of the deflected liquid jets will not be unduly impaired.

Although I have illustrated and described particular embodiments of my invention, I do not desire to be limited to the particular arrangements set forth, and I intend in the following claims to cover all modifications which do not depart from the spirit and scope of my invention.

I claim:

1. In dishwashing apparatus, jet producing means having a plurality of openings for discharging jets therefrom and movable by the reaction force developed by the jets, rotatable jet deflecting means for changing the direction of the jets comprising a body including a plurality of curved arms extending radially outward from the axis about which it rotates, each of said arms having a series of grooves disposed alongside one

another and shaped to keep the liquid essentially in the form of jets when leaving the grooves in each series one after another and while the direction of the jets is being changed by the latter, and said body being movable by the impact forces of the jets on said arms.

2. In dishwashing apparatus, jet producing means having an opening for discharging a jet therefrom and rotatable in one direction by the reaction force developed by the jet, rotatable jet deflecting means for changing the direction of the jet comprising a body including a member extending radially outward from the axis about which it rotates, said member having a series of grooves disposed alongside one another and shaped to keep the liquid essentially in the form of a jet when leaving the grooves in said series one after another and while the direction of the jet is being changed by the grooves, and said body being rotatable in the opposite direction by the impact force of the jet on said member.

3. In dishwashing apparatus, structure including rotatable jet producing means having an opening for discharging a liquid jet therefrom and rotatable jet deflecting means for changing the direction of the jet comprising a body including a member extending radially outward from the axis about which it rotates, said structure including provisions for rotating said jet producing means with respect to said jet deflecting means and for rotating said jet deflecting means with respect to said jet producing means, and said member having a series of grooves disposed alongside one another and shaped to keep the liquid essentially in the form of a jet when leaving the grooves in said series one after another and while the direction of the jet is being changed by the grooves.

4. Apparatus as set forth in claim 3 in which said grooves are disposed on a side of said member facing dishes adapted to be washed, said grooves having different lengths and being curved to change the direction of the jet, the lengths of said grooves extending through angles in a range which varies from a value below to a value above 90°.

5. Apparatus as set forth in claim 3 in which said grooves have liquid inlet ends, the axis of the jet opening and axis of the inlet ends of said grooves being substantially tangent to the same circle whose center is located substantially at the axis of rotation of said jet producing means.

6. In dishwashing apparatus, structure comprising a rotatable nozzle having an opening for discharging liquid radially outward therefrom and a rotatable liquid diverter, the axes of rotation of said nozzle and said diverter being substantially the same, said structure including provisions for rotating said nozzle with respect to said diverter and for rotating said diverter with respect to said nozzle, said diverter comprising a body for directing liquid in a multiplicity of directions toward dishes adapted to be washed, said body including a first region having portions at successively different radial distances from the axis of rotation of said diverter which are initially impinged by liquid discharged from said nozzle during rotation thereof, said body including a second region to which liquid passes from said first region and from which diverted liquid is directed toward the dishes to be washed, and said second region also having portions at successively different radial distances from the axis of rotation of said di-

verter and including portions respectively inclined radially outward from and radially inward toward the axis of rotation of said diverter, said portions of said second region at successively different radial distances from the axis of rotation of said diverter being inclined at different acute angles to such axis.

7. In dishwashing apparatus, rotatable jet producing means having an opening for discharging a liquid jet radially outward therefrom and movable in one direction by the reaction force developed by the jet, a rotatable liquid diverter movable in the opposite direction by the impact force of the jet acting thereon, the axes of rotation of said jet producing means and said diverter being substantially the same, said diverter comprising a body for directing liquid in a multiplicity of directions toward dishes adapted to be washed, said body including a first region having portions at successively different radial distances from the axis of rotation of said diverter which are initially impinged by the liquid jet discharged from said nozzle during rotation thereof, said body including a second region to which liquid passes from said first region and from which diverted liquid is directed toward the dishes to be washed, and said second region also having portions at successively different radial distances from the axis of rotation of said diverter and including portions inclined radially outward from the axis of rotation of said diverter and at an acute angle to such axis and also including portions inclined radially inward toward the axis of rotation of said diverter and at an acute angle to such axis.

8. Apparatus as set forth in claim 7 in which movement is imparted to said rotatable diverter by the impact force of the jet acting thereon, and structure operatively connected to said diverter for braking the movement imparted thereto by the jet.

9. In dishwashing apparatus, structure comprising a rotatable nozzle having an opening for discharging liquid radially outward therefrom and a rotatable liquid diverter, the axes of rotation of said nozzle and said diverter being substantially the same, said structure including provisions for rotating said nozzle with respect to said diverter and for rotating said diverter with respect to said nozzle, said diverter comprising a body for directing liquid in a multiplicity of directions toward dishes adapted to be washed, said body including a first region having portions at successively different radial distances from the axis of rotation of said diverter which are initially impinged by liquid discharged from said nozzle during rotation thereof, said body including a second region to which liquid passes from said first region and from which diverted liquid is directed toward the dishes to be washed, and said second region having portions at successively different radial distances from the axis of rotation of said diverter and including portions inclined radially outward from the axis of rotation of said diverter and at an acute angle to such axis and also including portions inclined radially inward toward the axis of rotation of said diverter and at an acute angle to such axis.

10. Apparatus as set forth in claim 9 in which said body includes a series of channels disposed alongside one another at successively different radial distances from the axis of rotation of said diverter, said channels having portions consti-

tuting the first region of said body which are initially impinged by liquid discharged from said nozzle and also having portions constituting the second region of said body from which liquid is directed toward the dishes to be washed, the axis of the nozzle opening and axes of the portions of the channels initially impinged by liquid discharged from the nozzle being substantially tangent to the same circle whose center is located substantially at the axis of rotation of said nozzle.

11. Apparatus as set forth in claim 9 in which said nozzle comprises structure having a plurality of openings for discharging liquid radially outward therefrom in the form of jets and said diverter comprises a plurality of radially extending members, each of said members being acted upon by the liquid jet discharged from each nozzle opening and constituting a body for directing liquid in a multiplicity of directions toward the dishes to be washed.

12. Apparatus as set forth in claim 9 in which said body includes a series of grooves disposed alongside one another at successively different radial distances from the axis of rotation of said diverter, said grooves having portions constituting the first region of said body which are initially impinged by liquid discharged from said nozzle and also having portions constituting the second region of said body from which liquid is directed toward the dishes to be washed.

13. Apparatus as set forth in claim 12 in which grooves in said series are curved in the direction of their length and have essentially the same radius of curvature and different arc lengths of which some are greater and some are less than 90°.

14. Apparatus as set forth in claim 13 in which the portions of said grooves constituting the second region of said body form an undulated line.

15. In dishwashing apparatus, rotatable jet producing means having a plurality of openings for discharging liquid jets radially outward therefrom and movable in one direction by the reaction force developed by the jets, a rotatable liquid diverter movable in the opposite direction by the impact forces of the jets acting thereon, said diverter comprising a body for directing liquid in a multiplicity of directions toward dishes adapted to be washed, said body including a plurality of curved arms extending radially outward from the axis of rotation of said diverter, each arm having a series of open grooves alongside one another which face the dishes to be washed, said grooves having liquid receiving regions at successively different radial distances from the axis of rotation of said diverter which are initially impinged by the liquid jets during rotation of said jet producing means, and said grooves having liquid discharge regions to which liquid passes from said liquid receiving regions and from which the diverted liquid is discharged toward the dishes to be washed, the liquid discharge regions of said grooves being at successively different radial distances from the axis of rotation of said diverter and including liquid discharge regions inclined radially outward from the axis of rotation of said diverter and at an acute angle thereto and also including liquid discharge regions inclined radially inward toward the axis of rotation of said diverter and at an acute angle thereto, said grooves being shaped to discharge liquid therefrom in the form of jets.

JOHAN FREDRIK ROBERT KARLSTRÖM.
